UNITED STATES PATENT OFFICE.

CHARLES W. DAKE AND JOHN E. KILKER, OF CHICAGO, ILLINOIS, ASSIGNEES TO PYLE-NATIONAL ELECTRIC HEADLIGHT COMPANY, OF CHICAGO, ILLINOIS, A CORPORATION OF NEW JERSEY.

TURBINE.

1,217,282.

Specification of Letters Patent. Patented Feb. 27, 1917.

Original application filed August 4, 1913, Serial No. 782,960. Divided and this application filed July 24, 1914. Serial No. 852,784.

To all whom it may concern:

Be it known that we, CHARLES W. DAKE and JOHN E. KILKER, citizens of the United States, residing at Chicago, in the county of 5 Cook and State of Illinois, have invented certain new and useful Improvements in Turbines, of which the following is a specification.

This case is a divisional application of No. 10 782,960, John E. Kilker and Charles W. Dake, bucket wheel and process of manufacturing same, filed August 4, 1913.

Our invention relates to turbines and the buckets therefor having reference to the 15 manner in which they are secured in position.

Figure 1 is a fragmentary side elevation with parts in section and parts removed of a rotor with buckets attached.

20 Fig. 2 is a section on line 2² of Fig. 1.

Fig. 3 is a section on line 3³ of Fig. 1.

Fig. 4 is a section on line 4⁴ of Fig. 1.

Fig. 5 is a perspective of one of the buckets.

25 Like parts are indicated by like letters throughout all the figures.

A is a bucket wheel, body or spider or disk of the usual type mounted upon a shaft running in bearings not shown. This plate 30 is flanged as at A¹, Figs. 3 and 4, in the usual manner and has a rim A² to which the separate buckets are to be attached. This rim is provided as shown in Figs. 3 and 4, with two circular slots, A³ and A⁴, inwardly converging each toward the other, thus leaving a mitered extension or rib A⁵ projecting outwardly from the rim A² and bounded on either side by the slots A³ and A⁴.

35 Recesses B¹ are located on either side of the rib A⁵ and form widened or increased areas of the slots A³ and A⁴. It will be noted from Fig. 3 that the walls B² B³ of 40 said recesses are parallel.

The turbine buckets C are mounted on the 45 rib A⁵ and consist of a bottom C¹, which is provided with two downwardly extending ears or lugs C²—C³, which project into the slots A³—A⁴ and grip the rib A⁵. The bottom C¹ of each bucket has upwardly projecting therefrom a bucket wall C⁴, which is perpendicular thereto, and this curved bucket wall forms the vane or bucket upon which the steam is designed to impinge. A flat top C⁵ projects outwardly from the

curved bucket wall, C⁴, being parallel with the bottom C¹ and is substantially the same size and shape, so that when the buckets are brought together as shown in Figs. 1 and 2 the open space between the bottom and the top walls of each bucket will be closed by 55 the side wall C⁴ of the next adjacent bucket.

D¹ are locking or calking rings of copper or other soft metal, which are tightly driven into the slots A³—A⁴ to hold the lugs C²—C³ firmly in position and to lock or fasten the 60 separate buckets separately in position on the rib A⁵ when they have been assembled into their desired position. D² is a welded, soldered or brazed joint as the case may be, between the outer free edge of the top C⁵ and 65 the back wall C⁴ of the adjacent bucket. One wall of each of the recesses B¹ is indicated in full lines in Fig. 3. The shape of the rib A⁵ would prevent the introduction of the buckets into slots A³ and B⁴, and in order that they 70 may be so introduced, the overhanging edges of the rib A⁵ are cut away as indicated in the full lines of Fig. 3 to form the recesses B¹ through which the lugs or ears C² and C³ of the buckets are introduced into the slots A³ and A⁴. The buckets if then pushed around 75 on the rib away from the recesses will be held in position by the overhanging edge of the rib.

We have shown our buckets as provided 80 with inwardly bent wings, and our rotor with a projecting flange or rib or ring integral with the rotor, but only as a preferred form for the parts could of course be very 85 differently shaped and differently connected together. The essential feature is that the buckets are assembled in a proper manner on the rotor, and secured in position thereon by two means, one a mechanical means which holds them in proper general relation 90 to each other, and the other a heat process means which holds the individual buckets together. In the particular form here illustrated, the buckets are inserted one by one so as to be held by the rib and then they are 95 welded, soldered, brazed or otherwise by some heat process secured together each to each. Of course they can all be put in position, and then each pair be secured together, or the two processes can be carried on together.

The buckets are made of thin, preferably sheet metal and are of uniform size and

shape and do not overlap each other. Such buckets without further attachment and secured one each to the rotor and driven in close proximity to each other are liable to 5 the objection that after a certain amount of use they break off. This breaking is due first to vibration induced by the passage of the steam from within the bucket across the edge of the lip C^5 between that lip and the 10 next adjacent bucket. The lip is suspended in the air so to speak without any support along its side edges or at its front, for it is impracticable to make such buckets particularly when they are stamped out so as to enable them to be forced together, the lip of 15 one against the back of the next so as to prevent the passage of steam. Such vibration tends eventually to crack the bucket either at the junction of the lip C^5 with the 20 back C^4 , or the bottom C^1 of the bucket with the back, or both.

When the buckets are assembled as indicated for example in Fig. 2 with the solder removed, the impact of the steam upon the 25 back of the bucket will also tend to strain the bucket at the line of connection between the back C^4 of the bucket and the bottom C^1 of the bucket. This is because the back C^4 has no rest or abutment against the lip C^5 .

30 It is to obviate these difficulties and to remove these objections that the invention here set forth was made, the lip being connected with the back or the place between

the bridge so as to prevent the escape of steam between them, prevent the vibration 35 of the lip C^5 , and give support to each back C^4 against the next adjacent lip so that in addition to the separate attachment of each bucket to the rotor they are all associated together so as to form, so to speak, a continuous or integral ring of buckets.

We claim:

1. A bucket wheel for steam turbines comprising a rotor with a series of thin metallic buckets separately secured thereon and shaped so that the lip of each closely approaches the outside of the back of the next, 45 said lips and backs connected together by a heat process so as to make an integral ring of buckets.

2. A bucket wheel for steam turbines comprising a rotor with a series of thin metallic buckets separately secured thereon and shaped so that the lip of each closely approaches the outside of the back of the next, 55 said lips and backs connected together by a heat process, including means for bridging the gap, so as to form an integral ring of buckets.

Signed at Chicago, Illinois, this twenty- 60 second day of July, 1914.

CHARLES W. DAKE.
JOHN E. KILKER.
